UNITED STATES PATENT OFFICE.

CHARLES W. YERGER, OF BOSTON, MASSACHUSETTS, ASSIGNOR TO THE CUTLER-HAMMER MFG. CO., OF MILWAUKEE, WISCONSIN, A CORPORATION OF WISCONSIN.

CIRCUIT CONTROLLER.

Application filed April 9, 1921. Serial No. 460,114.

To all whom it may concern:

Be it known that I, CHARLES W. YERGER, a citizen of the United States, residing at Boston, in the county of Suffolk and State 5 of Massachusetts, have invented new and useful Improvements in Circuit Controllers, of which the following is a full, clear, concise, and exact description, reference being had to the accompanying drawing, forming 10 a part of this specification.

This invention relates to circuit controllers particularly advantageous for controlling electric motors although not limited to such use.

15 Where sequentially responsive electro-magnetic switches are employed for accelerating an electric motor, it is often desirable to delay response of each switch for a definite time following response of the preceding switch to insure smooth acceleration and to afford a degree of protection to the controlled motor. To so time the response of the several switches, it has heretofore been proposed to employ a common control device 20 therefor to complete the circuits thereof sequentially, such device being retarded in its operation as by a dash pot and as an alternative it has been proposed to provide each switch with a dash pot to delay response thereof. However, both proposals have been found to be open to numerous objections including the unreliability of dash pots when used in the aforesaid relations and particularly when used to directly control switches of the size and character required for motor acceleration. Moreover 25 the single control device fails to provide for independent adjustments of the time elements of the several switches.

30 The present invention has among its objects to provide a controller for the aforesaid and other purposes having improved means of a simple and efficient character to definitely delay response of the desired switches.

35 Another object is to provide a controller of the aforesaid character wherein the means for delaying response of the switches permit of independent time adjustments for the several switches.

40 Another object is to provide a controller of such design that the desired delays may be accomplished by dash pots so employed as to render use thereof entirely practicable.

45 Another object is to provide for attain-

ment of the desired time control by simple and efficient relays which may be incorporated in controllers of present designs with little or no modification of the latter.

Another object is to provide for such control of switches supplied with either alternating or direct current.

Various other objects and advantages of the invention will hereinafter appear.

The accompanying drawing illustrates certain embodiments of the invention which will now be described, it being understood that the embodiments illustrated are susceptible of various modifications without departing from the scope of the appended 50 claims.

In the drawing,

Fig. 1 diagrammatically illustrates a controller for an alternating current motor;

75 Fig. 2 diagrammatically illustrates a controller which may be used for either direct or alternating current motors.

Referring to Fig. 1, the same illustrates in a simplified form a controller including 80 electro-magnetic switches 1, 2 and 3 for starting and accelerating an alternating current motor M of any preferred type. The switch 1 serves to connect the motor across alternating current supply lines L' and L² 85 through resistances R and R' while switches 2 and 3 serve to respectively short-circuit said resistances. As will appear, the energizing circuit of switch 2 is controlled by auxiliary contacts 1^a of switch 1 while the energizing circuit of switch 3 is controlled by auxiliary contacts 2^a of switch 2 whereby the switches 1, 2 and 3 are insured response sequentially in the order named.

The controller also includes relays 4 and 5 95 to respectively delay response of switches 2 and 3. These relays are of like construction, each comprising a switch arm 6 pivotally supported by magnet frame 7 and normally engaging a fixed contact 8. The magnet frame 7 has mounted thereon a winding 9 which when energized attracts the switch arm 6 away from contact 8 and said frame also has mounted thereon a dash pot 10 connected to the switch arm to oppose its return into engagement with contact 8. These relays control comparatively small currents and may therefore be designed to function in a positive and reliable manner under control of any one of numerous known types of 100 105 110

dash pots capable of adjustment and capable of functioning as described without opposing attraction of the switch arm by the winding 9. The relay 4 controls the energizing circuit of switch 2 while the relay 5 controls the energizing circuit of switch 3.

The winding 9 of relay 4 is connected in series with the winding of switch 1 while the winding 9 of relay 5 is connected in series with the winding of switch 2. Thus by properly proportioning the relay windings with respect to the windings of switches 1 and 2, each relay winding will be subjected to a heavy inrush of current upon initial closure of its circuit subject to a material reduction in current upon response of the switch 1 or 2 as the case may be. As will be understood the current supplied to each of the relay windings will be reduced as the impedance provided by its series connected winding increases whereas such impedance varies inversely as the air gap of the magnet involved, with the result aforesaid. In practice each relay is designed to respond to attract its contact arm out of engagement with its co-operating contact upon completion of its energizing circuit and to release its contact arm upon response of the switch to which its winding is connected.

It will thus be apparent that upon closure of the energizing circuit of switch 1, relay 4 will respond to disengage its contacts for interruption of the energizing circuit of switch 2 and that upon response of switch 1 said relay will re-engage its contacts subject to retardation of the dash pot 10 to complete the circuit of switch 2. Likewise it will be apparent that upon completion of the circuit of switch 2, relay 5 will be energized to disengage its contacts for interruption of the energizing circuit of switch 3 and that upon response of switch 2 said relay will re-engage its contacts subject to retardation by its dash pot to complete the circuit of switch 3. Thus the relay 4 provides for delaying response of switch 2 for a definite time after response of switch 1, the delay being determined by the adjustment of the dash pot whereas relay 5 delays response of switch 3 for a definite time after response of switch 2, this delay being determined by the adjustment of the dash pot of the latter relay. The relays accordingly provide for independent time adjustments for the switches 2 and 3.

The circuit connections are as follows. The motor circuit extends from line L' by conductor 11 through switch 1 and resistances R' and R² by conductor 12 to and through the motor by conductor 13 to line L², it being apparent that switches 2 and 3 respectively control short circuits around resistances R' and R². The energizing circuit of switch 1 extends from line L'

through a suitable control switch 14 by conductor 15 to and through the winding of said switch 1 by conductor 16 through the winding 9 of relay 4 by conductor 17 to line L². The energizing circuit of switch 2 extends from switch 14 by conductor 18 through auxiliary contacts 1^a of switch 1 by conductor 19 to and through the magnet frame of relay 4 and its contacts by conductor 20 to and through the winding of switch 2 by conductor 21 to and through the winding 9 of relay 5 by conductors 22 and 17 to line L². The energizing circuit of switch 3 extends from switch 14 by conductor 18 to and through the auxiliary contacts 2^a of switch 2 by conductor 23 to and through the magnet frame of relay 5 and its contacts by conductor 24 through the winding of switch 3 by conductors 25 and 17 to line L².

Referring to Fig. 2, the same illustrates similar electro-magnetic switches 30, 31 and 32 for starting and accelerating a direct or alternating current motor M' shown as provided with an armature a and series field f. The switch 30 serves to connect the motor M' across supply lines L³ and L⁴ through resistances R² and R³ while switches 31 and 32 serve to respectively short-circuit said resistances, the motor connections being substantially the same as in Fig. 1. Switches 30 and 31, like switches 1 and 2 of Fig. 1, are provided with auxiliary contacts 30^a and 31^a to interlock switches 30, 31 and 32 for response sequentially. Also switches 30 and 31 are respectively provided with auxiliary contacts 30^b and 31^b which normally short-circuit resistances r and r', each of such sets of auxiliary contacts being disengaged upon response of the switch with which the same are associated. The resistances r and r' are provided for inclusion in circuit with the windings of switches 30 and 31 respectively upon response of said switches to reduce the flow of current through their windings or in other words to serve as protective resistances.

Also this controller includes relays 33 and 34 of the same construction as the relays 4 and 5 of Fig. 1. The relays 33 and 34 have their operating windings respectively connected in series with the windings of switches 30 and 31 and said relays respectively control the energizing circuits of switches 31 and 32.

In this form of controller the winding of relay 33 will be subjected to a relatively heavy inrush of current upon completion of the energizing circuit of switch 1 whereas the current supplied to said relay winding will be reduced upon response of switch 1 and consequent inclusion of protective resistance r. Likewise the operating winding of relay 34 will be subjected to a relatively

heavy inrush of current upon completion of the energizing circuit of switch 31 whereas the current supplied to said relay winding will be decreased upon response of switch 31 and consequent inclusion of protective resistance r' . Thus these relays will function similarly to the relays shown in Fig. 1 to delay response of the resistance controlling switches the only essential difference between the controllers residing in the manner in which the current supplied to the relay windings is reduced for release of said relays.

The energizing circuit of switch 1 extends from line L^3 through a suitable control switch 35 by conductor 36 to and through the winding of switch 30 by conductor 37 to and through auxiliary contacts 30^a by conductor 38 to and through the winding of relay 33 by conductor 39 to line L^4 , the protective resistance r being included in said circuit upon response of switch 30. The energizing circuit of switch 31 extends from switch 35 by conductor 40 through the auxiliary contacts 30^a of switch 30 by conductor 41 to and through the magnet frame of relay 33 and its contacts by conductor 42 to and through the winding of switch 31 by conductor 43 through the auxiliary contacts 31^b by conductor 44 to and through the winding of relay 34 by conductors 45 and 39 to line L^4 . The energizing circuit of switch 32 extends from switch 35 by conductor 40 through auxiliary contacts 31^a of switch 31 by conductor 46 to and through the magnet frame of relay 34 and its contacts by conductor 47 to and through the winding of switch 32 by conductors 48 and 39 to line L^4 .

40 What I claim is new and desire to secure by Letters Patent is:

1. In a circuit controller, in combination, an electro-responsive switch acting upon response thereof to reduce the flow of current in its energizing circuit and an electro-responsive relay having its winding connected in series with the winding of said switch for energization therewith, said relay being adjusted to release upon reduction 50 of current in its circuit by response of said switch.

2. In a circuit controller, in combination, an electro-responsive switch acting upon response thereof to reduce the flow of current through its winding circuit and an electro-responsive relay having its winding connected in series with the winding of said switch for energization therewith, said relay being adjusted to release upon reduction 55 of current in its circuit by response of said switch and having means to delay its return to normal position.

3. In a circuit controller, in combination, a plurality of electro-magnetic switches and 60 an electro-responsive relay controlling one

of said switches, said relay having its winding connected in series with the winding of another of said switches for energization therewith and the latter switch upon responding effecting reduction of the current supplied to said relay winding to effect release of said relay.

4. In a circuit controller, in combination, a plurality of electro-responsive switches interlocked to respond sequentially and an electro-responsive relay responsive to delay energization of one of said switches, said relay having its operating winding connected in series with the operating winding of a preceding switch for energization therewith and for release by response of said preceding switch.

5. In a circuit controller, in combination, a plurality of electro-responsive switches to respond sequentially and an electro-responsive relay controlling one of said switches and normally occupying a position rendering the latter responsive upon response of a preceding switch, said relay having its operating winding connected in series with the winding of said preceding switch for energization therewith, said preceding switch upon responding effecting release of said relay and said relay having means for retarding its return to normal position.

6. In a circuit controller, in combination, a plurality of electro-responsive switches to respond sequentially, the first responsive switch having an energizing circuit wherein the flow of current is decreased by response of said switch and an electro-responsive relay controlling a succeeding switch and having its operating winding connected in the energizing circuit of said first responsive switch.

7. In a circuit controller, in combination, a plurality of electro-responsive switches interlocked to respond sequentially, one of the said switches having an energizing circuit wherein the flow of current is reduced by response thereof and an electro-responsive control relay for a succeeding switch responsive to prevent energization thereof and tending when de-energized to render said succeeding switch responsive, said relay having its operating winding connected in the energizing circuit of the first-mentioned switch and having means for retarding its return to normal position when released by the reduction of current effected by response 110 of the first-mentioned switch.

8. In a circuit controller, in combination, a plurality of electro-magnetic switches interlocked to respond sequentially, certain of said switches having independent energizing circuits wherein the current is reduced by response thereof, and a plurality of electro-responsive relays individually controlling certain of said switches, each of said relays having its operating winding 120

- 4
- connected in the energizing circuit of a preceding switch to be subjected to the varying current thereof for delaying response of the switch which it controls.
- 5 9. In a circuit controller, in combination, a plurality of electro-responsive switches to respond sequentially, one of said switches acting upon response thereof to increase the impedance of its energizing circuit and 10 an electro-responsive relay controlling a later responsive switch and having its operating winding connected in series with said first-mentioned switch to be energized therewith and to be released upon the increase in impedance of its circuit effected 15 by response of said first-mentioned switch.
10. In an alternating current circuit controller, in combination, a plurality of electro-responsive switches having operating windings supplied with alternating current and 20 an electro-responsive relay for controlling one of said switches, said relay having its winding connected in series with the winding of another of said switches to be energized therewith and to be released by the 25 reduction in current supplied thereto due to the increased inductance of the winding of the last-mentioned switch upon response of the latter.

In witness whereof, I have hereunto sub- 30
scribed my name.

CHARLES W. YERGER.
